RAIL FASTENER

Robert T. Woodings, Oakmont, Pa., assignor to
 Woodings-Verona Tool Works, Verona, Pa., a
 corporation of Pennsylvania

Application December 1, 1936, Serial No. 113,661

2 Claims. (Cl. 238—351)

This invention relates to fasteners for clamping railroad rails to metal supporting members such as tie-plates or structural members.

A great many types of fasteners have been suggested for this purpose, but they are either complicated in construction, expensive, difficult to apply or unsafe to use due to breakage. A further major disadvantage is that, as far as I know, none of them can be used with tie-plates provided only with ordinary spike holes for receiving them. That is, they all require tie-plate openings of special size and shape.

It is among the objects of this invention to provide a rail fastener, for clamping a rail to a metal supporting member, which is one-piece, inexpensive, durable, simple in construction, and adapted to be inserted through an ordinary spike hole or its equivalent.

In accordance with this invention a rail is clamped on a metal supporting member, such as a tie-plate or a structural member, by a unitary fastener that extends through an opening in the supporting member at the edge of the rail base. This opening may be an ordinary spike hole or the like which is generally square and in the neighborhood of three-fourths of an inch wide. The fastener has a vertical shank that extends through the opening, a laterally-extending arm at its upper end engaging the top of the rail base and a lateral projection at its lower end engaging the bottom of the supporting member. As the upper arm is distorted upwardly when the fastener is applied to the rail base, the rail is securely clamped to its supporting member. The upper portion of the shank of the fastener is substantially as large as the opening through the supporting member, whereby it is impossible, because of the lateral projection at its lower end, to insert the fastener in the opening in the ordinary way. To circumvent this difficulty the lower portion of the shank is beveled downwardly toward the lateral projection, so that when the shank is tilted at an angle to the axis of the opening the width of the portion being inserted is not quite as great as that of the opening. When the lateral projection reaches the lower end of the opening it is moved laterally under the bottom of the supporting member as the shank is brought to an upright position. The fastener is inserted in the opening when its upper arm is in some position other than above the rail base, but as soon as the shank is swung into upright position the fastener is turned until its upper arm engages the rail base up onto which it is then driven.

The upper arm is so formed that only its inner end engages the rail base, the remainder of the arm forming a bow through which the bending stress of distortion is distributed thereby decreasing the strain at any one point and greatly reducing the chance of breakage.

The preferred embodiment of the invention is illustrated in the accompanying drawing in which Fig. 1 is a vertical cross section through a rail and tie-plate supported on a cross tie with the fastener in clamping position; Fig. 2 is a fragmentary plan view of the fastener and associated members; Fig. 3 is an enlarged view taken on the line III—III of Fig. 2 and showing the position of the fastener as it is inserted through a tie-plate opening; Figs. 4 and 5 are views of the fastener taken from opposite sides; and Fig. 6 is a view, similar to Fig. 1, of the fastener clamping a rail to a metal structural member.

Referring to Fig. 1 of the drawing, a tie-plate 1, mounted on a cross tie 2 in the usual manner, is provided on its upper surface with a rib 3 extending transversely thereof and forming a shoulder that defines one side of a rail seat 4 and prevents lateral movement of the rail base 4 in that direction. The tie-plate is provided adjacent the opposite edge of the rail base with a vertical opening 6 which may be the ordinary substantially square spike hole found in common tie-plates (Fig. 2). Likewise, the cross tie may have a vertical hole 7 directly below the one in the plate as the result of a spike having previously been used with the tie-plate for holding the rail in place.

In order to hold the rail down on its seat in accordance with this invention, a one-piece fastening member or clamp 8 made from a rod bent to shape is disposed in the opening in the tie-plate with its shank 9 vertical. Projecting laterally over the rail base from the upper end of the shank is an arm 11 integral therewith, while the lower end of the shank has a lateral projection or lug 12, preferably in the same vertical plane as the arm, for engaging the bottom of the tie-plate. Consequently, the rail base and tie-plate are clamped together by the arm and lug of the fastener.

The major portion of the shank of the fastener is substantially as large as the tie-plate opening, so that the combined width of the upper portion of the shank and lug is greater than the width of opening 6 and it is therefore obviously impossible to insert the fastener in the opening in the ordinary way by merely moving

it downwardly with the axis of the shank vertical at all times. Nevertheless, it is a feature of this invention that, in spite of lug 12, the fastener can readily be inserted in the tie-plate opening. To make this possible, the lower portion of the shank is reduced in thickness so that by tilting the shank at an angle to the axis of opening 6 it can be inserted therein until the lug clears the lower end of the opening, whereupon the shank can be straightened up. The lug then engages the bottom of the tie-plate and thereby prevents the fastener from being removed as long as it is in an upright position.

Accordingly, as shown in Figs. 1 and 3, the lower portion of the shank on the side opposite to the lug is beveled downwardly toward lug 12 to such an extent that when the shank is disposed at an angle to the axis of opening 6 the width of the lower portion of the fastener, taken in a horizontal plane is less than the width of the opening (Fig. 3). This permits the lower end of the fastener to be inserted in the tie-plate opening. The length of the beveled portion is great enough to allow the tilted fastener to be inserted far enough into the tie-plate opening for the outer end of the lug to clear the lower end of the opening, as shown in Fig. 3. The fastener can then be moved into upright position because the lug can move laterally under the body of the tie-plate to the position shown in dotted lines in Fig. 3.

Before the fastener can be tilted for insertion in the tie-plate, its upper arm must be in some position other than overlying the rail base, such as parallel to the rail as shown in dotted lines in Fig. 2. As soon as the shank is straightened up in the tie-plate opening, arm 11 is swung laterally through an arc until it engages the top of the rail base and is then driven into position transversely thereof (Fig. 2), the inclination of the rail base distorting the arm upwardly. The lower end of the fastener is tapered somewhat, as shown in Figs. 1, 3 and 5, so that when there is no hole in the tie the fastener can be forced into it far enough to permit lug 12 to clear the bottom of the tie-plate opening. Likewise, whether or not there is a hole in the tie the shape of the lower end of the fastener aids the end of the lug in cutting into the tie when the fastener is straightened up, and in cutting its way through the tie when the fastener is turned to operative position.

It is also a feature of this invention that upper arm 11 is bowed downwardly from the shank and is provided adjacent its outer end with a seat 13 which is the only part of the arm that engages the rail base (Fig. 1). Consequently, due to the remainder of the arm being free of the rail base, when the fastener is turned to move the arm into position and the arm is distorted upwardly, the strain of the distortion is distributed throughout the length of the arm. As a result, breakage of the arm from distortion is substantially eliminated.

A rail fastener made in accordance with this invention can be successfully used with ordinary tie-plates adapted to receive, or which have actually been used with, railroad spikes. One-piece fasteners of this type known heretofore have required tie-plates of special construction or having openings of special shapes.

Another use that can be made of this fastener is in clamping rails to structural members such as I-beams on which the rails are supported.

This use is illustrated in Fig. 6 wherein a fastener 21 of the same general construction as that described above is shown clamping a rail 22 to an I-beam 23. The fastener extends through an opening 24 in the supporting beam, this opening being of substantially the same width as the portion of the fastener in the upper end thereof. To make it possible to insert the fastener in the opening, the lower end portion of the fastener is beveled so that it can be inserted when tilted at an angle to the axis of the opening.

According to the provisions of the Patent Statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A rail fastener for clamping a rail to a metal supporting member provided with a substantially square opening at the edge of the rail base, said fastener being in the form of a rod having a vertical shank and a laterally extending arm integral with the upper end of the shank for engaging the top of the rail base, the lower end of said shank being provided with a lateral projection for engaging the bottom of said supporting member, the lower portion of the shank being reduced in thickness whereby the fastener can be inserted in said opening only by tilting the shank at an angle to the axis of the opening until said lateral projection clears the lower end thereof and only when said arm is at the side of the rail base, said fastener being adapted to be turned in said opening to swing said arm into engagement with the top of the rail base, and said arm being reduced in thickness with its free end extending downwardly for engaging the top of the rail base at a point spaced inwardly from the edge thereof whereby the arm is adapted to be distorted upwardly by said base to thereby positively clamp the rail on said metal supporting member.

2. A rail fastener for clamping a rail to a tie plate mounted on a wooden tie and provided with a substantially square spike hole at the edge of the rail base, said fastener being in the form of a rod having a straight vertical shank and a laterally extending arm integral with the upper end of the shank for engaging the top of the rail base, the lower end of said shank being provided with a laterally projecting lug for engaging the bottom of said tie plate, the free end of the arm extending downwardly for engaging the top of the rail base at a point spaced inwardly from the edge thereof, the lower portion of the shank being reduced in thickness whereby the fastener can be inserted in said spike hole only by tilting the shank at an angle to the axis of the hole until said lug clears the lower end thereof and only when said arm is at the side of the rail base, said fastener being adapted to be turned in said hole to swing said arm into engagement with the top of the rail base, said arm being adapted to be distorted upwardly by the rail base to thereby clamp the rail on the tie plate, and said lug being provided with edges formed for cutting through said wooden tie as said fastener is turned in the tie plate hole.

ROBERT T. WOODINGS.
